(57) CLAIM

The ornamental design for a bra pad, as shown and described.

DESCRIPTION

FIG. 1 is a perspective view of a bra pad showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a bottom perspective view thereof; and,

FIG. 10 is a top perspective view thereof.

The broken line portions of the bra pad in FIGS. 1-10 represent unclaimed portions of the claimed design and form no part thereof. The broken lines of the bra in FIGS. 8-10 illustrate unclaimed environment and forms no part of the claimed design. The straps in FIGS. 1-7 are shown cutoff for ease of illustration.
